(57) **CLAIM**

I claim the ornamental design for a two-sided connectable companion computing device, as shown and described.

DESCRIPTION

This Design Patent Application is related to U.S. Design patent application Ser. No. 29/788,688, filed contemporaneously on Jul. 17, 2021, entitled “Connectable Companion Computing Device”, the entire contents of which is hereby incorporated herein by reference.

FIG. 1 is a front, bottom, right perspective view of a two-sided connectable companion computing device according to a first embodiment in which the connectors are extended, showing my new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is a front, bottom, right perspective view thereof according to a second embodiment in which the connectors are contracted, showing my new design;

FIG. 9 is a front elevation view thereof;

FIG. 10 is a rear elevation view thereof;

FIG. 11 is a left elevation view thereof;

FIG. 12 is a right elevation view thereof;

FIG. 13 is a top plan view thereof; and,

FIG. 14 is a bottom plan view thereof.

The broken lines shown in FIGS. 3-7 and 10-14 illustrate portions of the two-sided connectable primary computing device that form no part of the claimed design. The additional broken lines that show the graphical user interface shown in FIGS. 1-2 and 8-9 illustrate environment and form no part of the claimed design.
